UNITED STATES PATENT OFFICE.

ARTHUR W. SMITH, OF NEW YORK, N. Y., ASSIGNOR TO REMINGTON TYPEWRITER COMPANY, OF ILION, NEW YORK, A CORPORATION OF NEW YORK.

TYPE-WRITING MACHINE.

1,127,932.

Specification of Letters Patent.

Patented Feb. 9, 1915.

Application filed August 9, 1913. Serial No. 783,925.

To all whom it may concern:

Be it known that I, ARTHUR W. SMITH, citizen of the United States, and resident of the borough of Manhattan, city of New York, in the county of New York and State of New York, have invented certain new and useful Improvements in Type-Writing Machines, of which the following is a specification.

10 My invention relates to typewriting machines and more particularly to the line lock, margin stop and bell-ringer mechanism of such machines.

15 My invention has for its principal object to provide improved devices of the kind referred to.

To the above and other ends, my invention consists in certain features of construction and combinations and arrangements 20 of parts, all of which will be fully set forth herein and particularly pointed out in the claims.

In the accompanying drawings, Figure 1 is a partial front-to-rear vertical sectional 25 view of a typewriting machine having my invention embodied therein. Fig. 2 is a rear elevation, partly in vertical section. Fig. 3 is an enlarged isometric view of the margin stop bar and the adjustable stop devices. 30 Fig. 4 is a partial top plan view of the line lock mechanism.

In all of the views, parts are shown in section or broken away and parts of the machine are omitted.

35 My invention is applicable or adaptable to various styles of typewriting machines. The main frame of the machine shown in the drawings, comprises two side pieces, each having a base part 1, front and rear 40 corner posts 2, and a bar 3 connecting said posts at the top. Each of said side pieces also includes at its rear part an upward extension 4 and an inward and upward extending bracket 5. Said side pieces are 45 connected together by various cross bars and parts, including, in the base, a bar 6, and, farther back, a broad bar 7; and at the top said side pieces are connected by a front top plate 8 and a rear top plate 10, the latter 50 surmounting the upward extensions 4.

The carriage, which has a roller platen 11 journaled therein, comprises end pieces or brackets 12, and front and rear grooved rails 13, the latter constituting parts of 55 ball bearings which also include balls 14

and front and rear grooves in a stationary rail 15, which last is mounted on the bars 3 of the main frame. The end brackets 12 have a bar 16 secured thereto at their rear edges by means of screws 17. This bar is 6 here shown made of angled sheet metal. The carriage can be propelled in its travel leftward by any suitable means, such as a spring drum 18 having a cord 19 running over a pulley 20 and thence to a fixture 21 65 secured to the carriage. The feed of the carriage can be controlled by any suitable escapement mechanism, comprising, in the present instance, an escapement rack bar 22 mounted on the carriage by arms 23, and 70 coöperating feed dogs 24, here shown more or less conventionally, mounted on a dog rocker 25, pivoted in a bracket 26 secured to the under side of the stationary rail 15. Said dog rocker is shown provided with an 75 operating arm 27 and a restoring spring 28. Said arm 27 is adapted to be operated by an arm 29 projecting upward from a universal bar 30, pivoted at 31 in the base 1.

The printing instrumentalities can, as 80 far as my present invention is concerned, be of any suitable sort. In the present instance, they consist of types 32, on front strike type bars 33 which are pivoted at 34 in a type bar segment 35 which segment is capable of a case shift movement to different positions. To this end, said segment constitutes part of a shift frame which also includes side bars 36, each extending from the segment 35 first toward 85 the rear and thence upward, said bars being pivoted at their extremities on pivot pins 37, secured in the brackets 5 hereinbefore referred to. The pivots 37 are directly in rear of the front face of the platen 11. The 90 shift frame also comprises a cross bar 38, having a series of slots cut in its rear side in which slots are guided a series of bell crank sub-levers 39, pivoted on a wire 40. Said bell cranks have arms directed downward and connected by links 41 with the type bars 33, and other arms directed rearward and connected by vertical push links 42 with the rear ends of key levers 43 having keys 44 on their forward ends. Said 100 key levers are of the first order, being pivoted on wires 45, supported on the under side of the cross bar 7, and they are provided with returning springs 46. The construction is such that the depression of one 110

of the keys 44 causes its link 42 to push upward on the bell crank 39, and a type bar is operated by the link 41. In the present instance, each type bar has three types thereon and the shift frame, therefore, has three case positions, standing normally in its middle position, in which a line through the two ends of one of the links 42 would, if prolonged, pass substantially through the 10 axis of the pivots 37. When said frame is shifted the upper ends of the links 42 and the rear ends of the levers 39, move horizontally in a front-and-back direction, said links swinging about their lower ends as 15 pivots. It will be perceived that the sub-levers are mounted in the shift frame and partake of the case shift movements of said frame.

The type action and shift frame construction shown herein and above described, are not claimed in this case, but are claimed in a prior application of mine filed April 25th, 1913, Serial No. 762,582.

My line lock mechanism includes a locking member, preferably a locking bail 47, adapted to lock the sub-levers 39 and to do so, on occasion, in any one of the positions to which said sub-levers are shifted. Said bail, as here shown, consists of a cross bar having 25 two arms 48 and 49 pivoted by means of pivot screws 50 to the inner sides of the side bars 36 of the shift frame, the pivots 50 being above the rear ends of the sub-levers 39 and nearer to the pivots 37 of the shift 30 frame. The locking bail is made of sheet metal, and the cross bar 47 has a stiffening flange 51 bent down from its rear edge. The arm 49 is prolonged upward beyond its pivot 50 and at its upper end it has an ear 35 or pin 52 bent out therefrom and engaging in a slot in the lower end of a depending lug 53 bent down from one arm of a horizontal bell-crank 54, Fig. 4, which bell-crank is pivoted on a pivot screw 55, threaded into 40 the under side of the top plate 10. The lever 54 has an arm extending forward from the pivot 50 and having at its end a downwardly bent lug 56 having its lower end bifurcated to embrace a pin 57 projecting 45 from a margin stop and line lock bar 58. The construction is such that the top plate 10, which is secured to the parts 4 by screws, can be lifted vertically off of the machine, carrying the lever 54 with it, without disturbing the bail 47 or the bar 58. Said bar 58 lies back of and parallel with the carriage, and it is mounted for endwise motion toward the left from its normal position, such motion acting to rock the lever 54 and, 55 through said lever, the bail 47, causing said bail to move toward the front of the machine over the ends of the sub-levers 39, as indicated in broken lines in Fig. 1. When the shift frame is shifted, the pivots 50 of 60 the locking bail and said bail itself are

shifted also, and said bail is capable of locking the printing mechanism in any one of the three positions of said shift frame. The bar 58 at its right-hand end is formed or provided with a round pin or stud 59 which 70 takes a bearing in the right-hand extension 4 of the main frame. At its left-hand end said bar has a hole 60 extending longitudinally thereof, and into said hole there projects the reduced cylindrical end of a screw 75 61, which screw is threaded through the left-hand frame extension 4. A helical spring 62 in the hole 60, is compressed between the bottom of said hole and the end of the pin 61, and holds the bar 58 normally 80 in its right-hand position, in which position said bar holds the bail 47 in its rear or unlocking position. The bar 58 has enough freedom of movement toward the left, against the tension of the spring 62, to lock 85 the printing mechanism.

A bell-hammer 63 is mounted on the bar 58 by means of a wire arm 64 which, as here shown, consists of an extension of the pin 57; or rather, said pin 57 is merely the 90 upper part of the wire 64. The hammer 63 stands just forward of a bell 65 which is secured by a screw 66 to the base part 1 of the main frame, the arrangement being such that the bell can be rung by a rocking of the 95 bar 58 about the pins 59 and 61. Such rocking in one direction is caused by a spring 67 acting on the wire 57, 64, the motion of which under the impulse of said spring is limited by a stop pin 68 projecting from 100 the framework into the path of the wire at the upper part thereof. Said pin normally holds the hammer 63 a little away from the bell, as shown, so that, when the hammer is raised and dropped as will be presently explained, it strikes the bell by the springing of the parts.

A margin stop piece and a line lock and bell-ringer stop piece are adjustably mounted on the bar 58, which bar has, for this 110 purpose, a series of notches 69 cut in its under side or edge at letter space intervals. The line lock and bell ringer stop piece 70, as best shown in Fig. 3, consists of a piece of sheet metal punched out and bent up to 115 suitable form, and finished in certain respects that will be referred to. Said piece of sheet metal is so folded that the flat middle part of it comes behind the bar 58, whence the metal is folded forward above 120 and below the bar. At its upper edge, said stop piece has an ear 71 folded down in front of the bar 58, and serving as a guide to prevent backward motion of said stop piece, and two other ears 72 and 73, bent up 125 from the lower edge, perform a like function. The stop piece is thus folded around three sides of the bar 58, and from its free edges, guiding ears are folded against the fourth side. The ear 73 is at the left-hand end of 130

the stop piece, and it is bent first forward and then upward as shown, and constitutes the left-hand margin stop, which I also call the line lock stop. Said stop has its right-hand face abrupt, as shown, and its left-hand face or edge inclined, so as to cam up the carriage stop when returning from writing beyond line locking position, as will be explained presently. A bell-ringer lug or ear 74, projects toward the front of the machine from the upper edge of the stop piece 70, at its right-hand end, and, therefore, at a suitable distance to the right of the line locking stop 73. This ear projects horizontally forward, and it has its front edge inclined forward and toward the left, as shown, and its left-hand edge 76 beveled upward toward the right. The stop-piece 70 is wider up and down than the bar 58, and a flat spring 77, bowed downward in its middle, is under tension between the top of said bar and the upper fold of said stop piece, said spring acting to press the lower fold of said stop piece up against the teeth on the under side of said bar. Said spring is bent sharply upward at its ends so as to embrace the stop piece and to prevent said spring from escaping endwise. The bottom fold of the piece 70 has an ear 78 projecting from one end thereof and bent up as shown, so as to form a tooth which fits into one of the notches 69 in the bar 58, in which it is normally held by the spring 77. The construction is such that by pressing down with the finger on the stop-piece at its end, where said stop piece is roughened for the purpose, the tooth 78 is forced down out of engagement, after which the stop piece can be moved by the same finger along the rod in either direction to a new adjustment, and upon release of the pressure of the operator's finger, the spring 77 will cause the tooth 78 to engage a notch 69 and lock the stop-piece in its new position. It will be perceived that the stop piece consists of a single piece of sheet metal.

The stop on the carriage for coöperation with the devices just described, is mounted or formed on a lever 80, pivoted at 81 to the rear side of the bar 16, said lever extending lengthwise of the carriage and having its inner end at about the middle of the carriage and its outer end at one end of the carriage. This lever is shown as made of sheet metal, and at its inner end it has two ears 82 and 83 bent off therefrom toward the rear of the machine, the former from the upper edge and the latter from the lower edge of the lever, so that these ears lie with their flat sides horizontal and one above the other. The upper ear 82 stands in line with the ear 74, with which it is adapted to coöperate to ring the bell. As the carriage travels toward the left, when the ear 82 reaches the ear 74, it moves across the inclined front edge of

said ear 74, as shown in Fig. 4, camming said ear toward the rear and rocking the bar 58 against the tension of the spring 67 and against the weight of the hammer 63. When the ear 82 passes the ear 74, the bar 58 and hammer 63 drop back and the bell is sounded. On the return of the carriage to the right, the ear 82 rides up on the incline 76, rocking the lever 80 slightly, so that said ear 82 can move back to the right without disturbing the bar 58, or being itself arrested by the lug or ear 74. After the sounding of the bell, a few more steps of the carriage brings the ear or stop 83 into contact with the abrupt edge of the stop 73, moving the bar 58 toward the left and swinging the bail 47 to locking position, and also arresting the carriage. In order to provide for writing additional letters after the operation of the line lock, the lever 80 can be rocked to raise the ear 83 above the upper edge of the stop 73, whereupon the spring 62 will move the bar 58 to the right, and move the stop 73 in underneath the ear 83. The carriage can then step farther to the left. When the ear 83 passes the stop 73, it drops down to normal position; but it does not prevent the carriage from being freely drawn to the right, as the inclined left-hand edge of the stop 73 then cams the ear 83 upward, so that said ear rides freely over the stop.

In order to provide for the above-described motions of the lever 80, said lever has its outer end so formed and bent as to constitute a margin and line lock release key 84, lying flatwise over the top of the end-piece 12 of the carriage. By depressing this key, the lug 83 can be elevated to clear the stop 73 as above described. The key and lever are held in normal position by a returning spring 85 mounted in a hole in the end piece 12 and compressed between the bottom of said hole and the under side of the key 84. The motion of the lever under the impulse of said spring is limited by an ear 86, bent off from the upper edge of the lever and lying over the bar 16, and also, for guiding purposes, bent down in front of said bar.

A margin stop piece 87 is made of sheet metal and is mounted on the bar 58 in a way generally resembling that of the piece 70. It has a guiding flange 88 bent down and another 89 bent up in front of the bar 58, and it has also a stop 90 projecting therefrom like the stop 73 in all respects except that it is reversed, having its abrupt edge at the left and its inclined edge at the right. This stop coöperates with the ear 83 to arrest the carriage when the latter is drawn toward the right. The carriage can be drawn farther back to write in the margin if desired, by operating the key 84, and in that case the ear 83 will be cammed up by the inclined part of the stop 90 when the carriage moves toward the left, so that said

stop in no wise interferes with leftward motion of the carriage. The stop piece 87 is provided with a locking tooth 91 and spring 92, resembling the corresponding parts of 5 or associated with the piece 79. The upper edge of the bar 58 can be suitably graduated to facilitate the setting or adjustment of the margin stops thereon. It is here shown with two sets of graduations, one from "0" 10 to "30" for the margin stop 87 and the other from "50" to "80" for the line lock stop.

There is also provided a final line-locking stop 93, consisting of a piece of metal secured by a screw 94 to the left-hand end of the bar 58, and projecting first forward and thence upward in the path of the ear 82. This stop projects upward so high that it cannot be cleared by depressing the release 20 key 84, so that, when the carriage reaches its extreme left-hand position, the line-lock is operated and cannot be released by said key.

Any suitable means can be employed to 25 shift the shift-frame 35, 36, 38. The particular means diagrammatically shown in the present instance is not of my invention but is of the invention of Edwin E. Barney. This comprises a lever 95, pivoted at its 30 middle at 96 to one side or end of the segment 35, a toggle 97, 98, pivoted to one end of said lever and anchored at 99 to the bar 3, and a toggle 100, 101, pivoted to the other end of said lever and anchored at 102 to the 35 base 1, said toggles being normally straight and between them holding the lever 95 and segment 35 in middle position. When the first of these toggles is broken, it pulls upward on the forward end of the lever 95, 40 the rear end of said lever taking a fulcrum on the upper end of the link 100, and the segment 35 is, therefore, shifted upward from normal. When the other toggle is broken, the rear end of the lever 95 is pulled 45 downward, the forward end of said lever taking a fulcrum on the link 97, so that the segment is then shifted downward. The upper toggle 97, 98 is operated by a shift-key lever 103, pivoted at 102, and having a 50 link 104 connecting it with a lever arm 105 integral with the link 98. The toggle 100, 101 is operated by another shift key lever 106, pivoted between its ends at 107, and having pin-and-slot connection 108 with a 55 lever arm 109, integral with the link 101. Suitable returning springs keep the toggles normally straight.

Various changes can be made in the details of construction and arrangement without departing from my invention.

What I claim as new and desire to secure by Letters Patent, is:—

1. The combination with a carriage, a platen, printing mechanism, and means for shifting said printing mechanism to differ-

ent case positions, of line lock mechanism coöperating with said shiftable printing mechanism in the different case positions thereof.

2. The combination with a carriage, a 70 platen, and printing mechanism, said printing mechanism having a case shift motion, of line lock mechanism acting to lock said shiftable printing mechanism and including a locking element that shifts with said shiftable mechanism.

3. The combination with a carriage, a 75 platen and printing mechanism, said printing mechanism having a case shift motion, of line lock mechanism including a locking bar shiftable with said printing mechanism and acting to lock said printing mechanism in its different positions.

4. The combination with a carriage, a platen and printing mechanism, said printing mechanism having a case shift motion, of line lock mechanism including a locking bar shiftable with said printing mechanism and acting to lock said printing mechanism in its different positions, a bar moved by 80 said carriage at the end of a line, and a lever mounted on the stationary frame work and connecting the last mentioned bar with said locking bar.

5. The combination with a carriage, type 85 bars, printing key levers, and connections between said key levers and type bars including sub-levers, of line lock mechanism including a locking bar movable into and out of position to lock said sub-levers.

6. The combination of a carriage, a 90 platen, printing keys, sub-levers operated by said keys, printing instrumentalities operated by said sub-levers, case shift mechanism for shifting said printing instrumentalities and said sub-levers, and line lock mechanism coöperating with said sub-levers and shiftable therewith.

7. The combination with a carriage, type 95 bars, sub-levers for operating said type bars, keys for operating said sub-levers, and a shiftable frame in which said type bars and sub-levers are mounted, of line lock mechanism including a locking bar arranged for coöperation with said sub-levers.

8. The combination with a carriage, type 100 bars, sub-levers for operating said type bars, keys for operating said sub-levers, and a shiftable frame in which said type bars and sub-levers are mounted, of line lock mechanism including a locking bar arranged for coöperation with said sub-levers, said bar mounted in said shiftable frame.

9. The combination of a carriage, key 105 levers of the first order, push links operated by said key levers, bell cranks operated by said push links, type bars operated by said bell cranks, and line lock mechanism including a bail arranged to be rocked over said bell cranks.

- " 10. The combination of a carriage, line lock mechanism including a bar mounted behind said carriage and having adjustable stops mounted thereon for coöperation with said carriage, said bar movable by said carriage, a swinging bail in the back part of the machine, a lever connecting said bar and bail, and printing mechanism including key levers and parts operated thereby, 10 certain of said parts being in position to be locked by said bail.
11. The combination of a carriage, a margin stop bar mounted in the stationary framework for sliding and rocking motion, 15 a line lock stop device adjustable along said bar and having two contact parts, one above the other, a lever on said carriage having two contact parts, one for each of the contact parts on said adjustable stop device, 20 one of said contact parts being adapted to rock the bar, and the other being adapted to move the bar lengthwise, and means for rocking said lever to move said parts out of coöperative position.
- 25 12. The combination with a carriage and printing mechanism, of bell-ringer and line lock mechanism including a lever on the carriage having two contact parts that travel in different paths, coöperating devices on the stationary frame work, a bell sounded by one of said devices, a line lock operated by the other of said devices, and means for rocking said lever to move said contact parts out of line with said devices.
13. The combination with a carriage and printing mechanism, of a lever on said carriage and having two lugs thereon, a bell ringer operated by one of said lugs, a line lock operated by the other lug, and means for rocking said lever to move said lugs out of coöperation with said bell ringer and said line lock.
14. The combination with a carriage and printing mechanism, of a lever on said carriage and having two lugs thereon, a bell ringer operated by one of said lugs, a line lock operated by the other lug, a margin stop coöperating with one of said lugs, and means for rocking said lever to move said lugs out of coöperation with said bell ringer, 50 said margin stop and said line lock.
15. The combination with a carriage and printing instrumentalities, of a sheet-metal lever on said carriage and having two ears bent off therefrom, a bell ringer operated by one of said ears, a line lock, a margin stop coöperating with the other of said ears, and means for rocking said lever into and out of position for coöperation with said bell ringer and line lock.

Signed in the borough of Manhattan,
city of New York, in the county of New
York, and State of New York.

ARTHUR W. SMITH.
